[57] CLAIM

The ornamental design for a water pitcher, as shown
and described.

DESCRIPTION

FIG. 1 is a top, right perspective view of a water
pitcher showing our new design, the left side perspec-
tive view being a mirror image thereof;

FIG. 2 is a rear elevational view thereof;

FIG. 3 is a front elevational view thereof;

FIG. 4 is a top plan view thereof; and,

FIG. 5 is a bottom plan view thereof.

FIG. 1

FIG. 2

FIG. 4

FIG. 3

FIG. 5
